HYDRAULIC JACK

Joseph J. Mueller, St. Joseph, Mich., assignor to
 Auto Specialties Manufacturing Company, St.
 Joseph, Mich., a corporation of Michigan

Application September 2, 1944, Serial No. 552,447

4 Claims. (Cl. 60—52)

1

This invention relates to hydraulic jacks and more particularly to hydraulic automobile jacks.

Among the objects of the present invention are to provide an hydraulic jack of the foregoing character wherein the high pressure pump cylinder and/or ball valve cage are formed of few parts which may be assembled exteriorly of the jack and then assembled within the jack body in such a manner as to permit for ready disengagement from the body of the jack for repair or replacement; to provide an hydraulic jack, particularly of the automobile type, wherein the high pressure pump cylinder comprises a preformed sleeve having internal highly polished metal walls of uniform diameter throughout the length of the sleeve and wherein the exterior of the sleeve is threaded except for at least a plurality of countersunk angularly disposed portions disposed intermediate the threaded ends of the sleeve so as to provide gripping surfaces adapted to be contacted by a tool for turning the sleeve into or out of a threaded bore in the wall of the jack body to facilitate the assembly or disengagement of the high pressure pump cylinder from the jack body.

Yet another object of the invention resides in providing as an article of manufacture a cheap, economical construction for a cylinder for a high pressure pump for an hydraulic jack, comprising a cylindrical metal sleeve having a high polished exterior and having external threads, an intermediate portion of the threaded portion of the sleeve being cut away to provide angularly disposed walls located below the curved plane of the threaded peripheral surface of the sleeve adapted to be engaged by a tool for turning the sleeve so that it may be assembled or demounted from a threaded bore in the body of the jack.

Yet another object of my invention resides in providing a ball valve cage for a hydraulic jack comprising a single metallic fitting interiorly bored to provide oil passages and adjacent valve seats and having balls to seat upon said valve seats, the arrangement being such that the ball valve cage is assembled in a bore in the body of the jack in such a manner that the walls of the bore maintain one of the ball valves relatively close to its seat while permitting it to shift therefrom.

These and other objects of the invention will be apparent from a perusal of the following specification taken in connection with the accompanying drawings, wherein:

Figure 1 is a front elevational view of the im-

2

proved jack, the upper part being shown in cross section;

Figure 2 is an end or side elevational view of the jack shown in Figure 1;

5 Figure 3 is a plan section taken on the line 3—3 of Figure 1;

Figure 4 is an enlarged cross sectional view taken on the line 4—4 of Figure 2;

Figure 5 is a detailed cross sectional view of 10 the liquid release or by-pass mechanism taken on the line 5—5 of Figure 3;

Figure 6 is a perspective view of the high pressure pump cylinder sleeve;

Figure 7 is a cross sectional view taken on the 15 line 7—7 of Figure 6; and

Figure 8 is a perspective view of the ball valve cage.

While the invention has been illustrated in 20 connection with the type of jack shown in the drawings, to wit a jack having a base suitably counterbored to provide a central ram cylinder well and a surrounding reservoir well with two concentric sleeves arising therefrom and carried by the base, the ram cylinder, the inner sleeve, 25 the outer sleeve, the concentrically surrounding reservoir and the base carrying additional relatively smaller boring preferably angularly disposed with respect to the vertical axis of the ram cylinder to provide a high pressure pump, it is 30 to be understood that certain features of this present invention may be otherwise adaptable to other types of jacks and the claims are not, unless otherwise limited, to be construed only to the type of jack shown in Figure 1.

35 Therefore, for purposes of illustration and exemplification only the invention is described in connection with the type of jack wherein the base is formed as a single integral casting 2 having a centrally formed, countersunk well 4 and a concentrically surrounding well 6 providing shoulders 8 and 10. An upstanding sealed sleeve 12 having threads 14 at its lower end screws into threads formed into the upper portion of the central countersunk well portion 4 to provide a ram cylinder, 40 and a second cylindrical sleeve 16 is mounted in the countersunk shoulder portion 10 of the base. As shown in Figure 1 the upper portion of the ram cylinder sleeve 12 is threaded as at 18 to receive a cap 20 which is constructed to clamp 45 the reservoir sleeve 16 in position. This cap 20 is provided with a central opening 22 through which the ram 24 is adapted to pass. This ram carries a load support 26 at its upper end and carries a suitable piston 26—28 at its lower end.

50 In the present construction of the jack this

single integral basal casting 2 is provided with a preferably obliquely disposed, relatively smaller bore 50, the projection of the axis of which intersects the central axis of the ram cylinder 12 at an acute angle, the basal casting being provided with a relatively small boring 32 which connects the bottom of the reservoir 34 with this boring 30. The bore 30 is adapted to receive the high pressure pump mechanism.

In addition, the basal casting is provided on its underside with a cast pocket 36 which opens downwardly and is preferably disposed in a slightly angularly, upwardly extending direction longitudinally, the inner end of this pocket being provided with a threaded bore 38 and with a relatively smaller bore or passage 40 which extends slightly inwardly and upwardly to connect with the central cast well 4 of the base. In addition, when the bore 30 is formed for the high pressure pump cylinder the bottom of this bore 30 is provided with preferably inclined or chamfered walls 42 and also with a centrally disposed relatively smaller bore or passage 44 which laterally connects with the bore or passage 40 so that the high pressure pump cylinder bore connects by means of the bores 44 and 40 with the central well 4 of the ram cylinder and also by means of the bore 32 with the reservoir. A suitable threaded plug 46 closes the end of the bore 40, this plug 46 being located in the threaded bore 38 in the pocket 36 and accessible from the underside of the jack. The bore 30 extends from the chamfered portion 42 outwardly and is of preferably uniform diameter except for the threaded portion 48 thereof which preferably is of larger diameter than the portion 30. In addition, the upper portion of the base at the mouth of this bore 30 is slightly countersunk as at 50 to form a seat for packing.

This counterbore 30 is adapted to receive a preferably unit assembly of a high pressure pump cylinder and piston. One of the main features of my invention resides in the construction of the high pressure pump cylinder which in the present instance is formed so simply and economically as to considerably reduce the cost of manufacture and assembly of the jack. In the present instance this high pressure pump cylinder is formed as a tubular, cylindrical, elongated, metallic sleeve carrying an interior relatively high metal polish so as to function as a high pressure pump cylinder for the reciprocation of the piston therewithin. This sleeve is preferably of uniform thickness throughout except as hereinafter specified and is of uniform diameter within. It is threaded externally and as originally made is threaded continuously from one end to the other. After the sleeve is threaded, however, it is preferably slabbed by a milling cutter to provide a plurality of angularly disposed, preferably plane faced facets which provide gripping surfaces for a ring or other tool whereby the sleeve may be turned into its threaded bore in the base or whereby it may be unturned therefrom. In the formation of this sleeve I propose to start with a relatively long pipe or tubular cylinder which is preformed with the exact high metal polish. This pipe may either carry initially a thread throughout its length or may be thereafter threaded. The threaded pipe is then cut into sections of desired ultimate length corresponding to the length of the high pressure pump cylinder and then a series of these lengths are held in a fixture and slabbed as a gang by suitable cutting means such as a milling cutter, the arrangement being such that the milling cutter slabs the facets angularly

about the circumference of the sleeves, a number of sleeves being slabbed at the same time. Alternatively, the elongated pipe may be slabbed at the required places and then cut into desired points to form the sleeve. It is to be understood that the exact type of turning surface is not restricted to the slab portion shown. In fact, any desired type of tool gripping surface may be made. It is important, however, that the threaded surfaces 52' and 54 be disposed at the ends of the slabbed portion 56 for purposes which will hereinafter appear.

The valve mechanism for the high pressure pump cylinder comprises a unitary metal ball valve cage 58 having a conical nose 59 seating on the circular edges of the bore 44 connecting the valve cage of the high pressure pump cylinder with the ram cylinder. This cage is provided with a longitudinal passage 60 which opens at opposite ends of the cage and is provided with an enlargement forming a valve seat 64 against which a ball valve 66 is adapted to seat. In addition the cage is provided with another longitudinally extending bore 70 which opens on opposite sides of the cage and is provided with a valve seat 72 against which the ball valve 74 is adapted to seat. In addition this valve cage is provided with a peripheral cut-out or recess 76 which communicates with a lateral bore 78 in turn communicating with the bore 70. The diameter of this valve cage is less than the diameter of the bore 30. The valve cage is preferably provided with a narrower portion 80 which is adapted to make a tight wedging fit in one end, to wit the lower end, of the threaded sleeve 52, whereby the sleeve and the ball valve cage may be united to form a removable unit. Alternatively they may be severable as separate units. The innermost part of the bore 30 is not threaded and is preferably of smaller diameter than the threaded part 48 of the bore. The end of the bore 30 is conically shaped and is centrally apertured as at 44 to provide a passage interconnecting the ball valve cage and the passage 40 connecting with the ram cylinder.

Reciprocably mounted within the cylindrical sleeve 52 is the piston rod 82 having formed on its lower end in any desired manner a piston 83, the upper end of the piston rod being provided with a lateral cut-out 84 for engaging with a pin 86 mounted on a handle 88 which is pivotally mounted as at 90 on a strap 92 welded as at 94 and 95 to the exterior of the sleeve 16. The pin 90 forms a pivotal point about which this handle 88 may pivotally swing. The handle in turn is provided with two outstanding relatively long lugs 96 and 97 which may be grasped to lift the jack. The hollow socket 88 of the handle may receive an elongated bar to assist in reciprocation of the pump piston 82 in its cylinder sleeve 52.

A packing 98 surrounds the lower threaded portion 52' of the sleeve and lies in the seat 50. This packing is held in place by a packing ring 100 which engages the lower threads 52' of the sleeve and thus tightly confines the packing 98 to prevent leakage along the threaded engagement of the tubular sleeve with the base. In addition the outer end of the tubular sleeve is provided with a ring 102 which confines an additional packing 104 between its closed end 106 and the upper threaded end of sleeve 52. This ring 102 threads on the upper threaded portion of the sleeve 52, and the piston rod 82 reciprocates therethrough. Thus it will be seen that the threaded portion 52' is considerably longer than the upper threaded

portion 54, whereby the threaded portion 52' functions not only to engage the threads 48 of the basal bore 30 but also to engage the threads of the packing collar 102, whereas the packing collar 102 is the only element that engages the upper shorter threads 54 of the sleeve to hold the packing 104 in position.

Means is provided for relieving the liquid in the ram cylinder in order to permit the ram 24 to descend. This means comprises a by-pass or release valve shown particularly in Figures 2, 3 and 5. This release construction is effected by providing the one piece basal casting with a bore 108 formed through the walls thereof and disposed in a downwardly inclined direction. This bore at its inner end is provided with converging walls 110, the central portion of which communicates with a smaller bore 112 in turn communicating with the ram cylinder well 4. In addition the walls of the base are provided with a lateral bore 114 which connects with the enlarged bore 108 and also with the reservoir 34. The bore 108 at its outer end communicates with an enlarged bored portion 116 formed in the base which is provided with threads 118 adapted to receive a bored thimble 120, the inner and outer walls of which thimble are threaded, the outer walls engaging the threads 118 and the inner walls engaging threads of the by-pass valve rod 122. The inner end of the valve is provided with converging walls 124 which seat upon the valve seat 110 to close communication between the passages 112 and 114. The outer end of the thimble 120 is hexagonal for turning and the outer end of the valve rod 122 is provided with a head 126 having the turning rod 128. It will be noted that the valve rod is disposed laterally of a vertical plane passing through the center of the high pressure pump cylinder. This is shown in Figure 2. When the release valve 122 is closed on its seat 110 and the pump piston rod 82 is reciprocated upon the up stroke of the piston, liquid will be drawn from the reservoir 34, through the passage 32, thence around the recess 76 of the ball cage, thence through the opening 78 thereof into the passage 70, the suction of the piston lifting the ball 74 from its seat to cause the liquid to pass into the high pressure pump cylinder. At this time the ball valve 66 is held to its seat by the suction. Upon the down stroke of the piston this liquid will be transferred through the passage 60 past the ball 66 into passage 44, thence into passage 40 and thence into the ram cylinder to raise the ram. During this latter movement the ball valve 74 is held on its seat. It will be noted that the ball valve 66 will be held relatively close to its seat 64 by the conical nose 59. Any other desired means, such as a wire, may be used for holding the ball 74 close on its seat. When necessary, by operation of the valve 126 the communication is established between the passages 112 and 114 so that liquid in the ram cylinder may be released back to the reservoir 34 to cause the ram to descend.

Obviously the invention is not limited to the specific details of construction disclosed herein but is capable of other modifications and changes without departing from the spirit and scope of the appended claims.

Having thus described the invention, what is claimed as new and desired to be secured by Letters Patent is:

1. An hydraulically actuated device including in combination a base having a ram cylinder thereon, said base including a bore communicating with said ram cylinder, the outer portion of

the internal wall of the bore being threaded, a high pressure pump cylinder for said device comprising an elongated sleeve having its opposite ends externally threaded, said externally threaded sleeve portions being of uniform diameter throughout and the outer wall of the sleeve between the threaded portions being polygonal, the thread at one end of said sleeve being a continuation of the thread at the other end thereof, the inner threaded end of the sleeve engaging the internal threads of said bore and a portion of said threads projecting beyond the mouth of the bore, and a valve cage mechanism located in the innermost end of said bore, said polygonal portion of said sleeve and the outermost end of the sleeve projecting beyond the mouth of the bore, a pump piston reciprocably mounted in said sleeve, packing means surrounding that portion of the threaded end of the sleeve that projects beyond the mouth of the bore, and a threaded ring threadedly engaging that portion of the threads of the sleeve projecting beyond the mouth of the bore whereby clampingly to engage the packing between the mouth of the bore and the external threads of the sleeve, and an internally threaded ring threading onto the external threads of the outer end of said sleeve, and packing means confined between the internal threaded ring, the outer end of said sleeve, and the piston reciprocably passing through said sleeve and ring.

2. An hydraulically operated device comprising a base including a ram cylinder, said base having a bore, the outer portion of which is internally threaded, a high pressure pump cylinder for said bore comprising an elongated sleeve of uniform wall thickness throughout its length and having a circular inner bore throughout its length of uniform internal diameter and circular threaded outer surfaces at each end of the sleeve of uniform outer diameter, a thread of each of said outer surfaces being a continuation of the thread of the other outer surface, the outer surface of the sleeve between the threaded portions being polygonal, one of said threaded portions of the sleeve threadedly engaging the internal threads of the bore.

3. An hydraulically operated device comprising a base including a ram cylinder, said base having a bore the outer portion of which is internally threaded, a high pressure pump cylinder for said bore comprising an elongated sleeve having a circular inner bore throughout its length and circular threaded outer surfaces at each end of the sleeve, a thread of each of said outer surfaces being a continuation of the thread of the other outer surface, the outer surface of the sleeve between the threaded portions being polygonal, one of said threaded portions of the sleeve threadedly engaging the internal threads of the bore, the polygonal shaped outer portion of the sleeve having its polygonal surfaces a smaller radial distance from the axis of the sleeve than the circular portions of the ends of the threaded portions.

4. An hydraulically actuated device including in combination a base having a ram cylinder thereon and a surrounding oil-containing reservoir, said base including a bore the inner end of which is of conical shape and the center of said conical shaped portion being apertured, means forming a passageway in the base for connecting the reservoir with the inner end of said bore, said base having a passageway communicating with said aperture of said conically shaped portion and connecting with the ram cylinder, a sleeve threading in said bore, a piston re-

ciprocable in said sleeve, a valve cage having a countersunk portion forming a tight wedging fit in the inner end of said sleeve, said valve cage having a centrally apertured conical nose closing upon the conical apertured portion of the inner end of said first mentioned bore, the opposite end of said nose having a countersunk peripheral portion making a tight fit in the lower end of said cage, said valve cage including a first liquid passage communicating with the central aperture of said conical nose and with the piston chamber above said valve cage, said passage having a valve seat and a valve resting on said seat, the inner wall of said nose forming an abutment to limit movement of said valve away from its seat, said valve cage including a second passage communicating with the piston chamber above said cage and having a lateral passage communicating with the passage that connects with the reservoir, said second mentioned passage in said valve cage having a valve seat and a valve resting thereon.

JOSEPH J. MUELLER.
